UNITED STATES PATENT OFFICE

115,536

DESIGN FOR A BROILER

Charles E. Zimmerman, Chicago, Ill.

Application September 12, 1938, Serial No. 79,845

Term of patent 3½ years

To all whom it may concern:

Be it known that I, Charles E. Zimmerman, a citizen of the United States, resident of Chicago, in the county of Cook, State of Illinois, have invented, a new, original, and ornamental Design for a Broiler, of which the following is a specification, reference being had to the accompanying drawing, forming a part thereof, wherein

Fig. 1 is a perspective view of a broiler showing my design.

Fig. 2 is a top plan view of the same.

I claim:

The ornamental design for a broiler, as shown.

CHARLES E. ZIMMERMAN,
